UNITED STATES PATENT OFFICE.

ETNA H. DAVIS, OF ELMIRA, NEW YORK.

NON-REFILLABLE BOTTLE.

SPECIFICATION forming part of Letters Patent No. 761,362, dated May 31, 1904.

Application filed October 24, 1903. Serial No. 178,342. (No model.)

To all whom it may concern:

Be it known that I, ETNA H. DAVIS, a citizen of the United States, residing at Elmira, in the county of Chemung and State of New York, 5 have invented certain new and useful Improvements in Non-Refillable Bottles, of which the following is a specification.

This invention relates to improvements in bottles in which provision is made to prevent the refilling thereof with liquid after they have once been emptied; and my object is to provide a simple and effective arrangement of the parts which constitute such non-refilling device and to so position them that there will be a full and unrestricted flow of liquid from the bottle when pouring therefrom.

A bottle embodying my invention is illustrated in the accompanying drawings, in which—

20 Figure 1 represents a vertical transverse section of the bottle, and Fig. 2 a bottom plan view of the hood or cap-piece G removed.

Like letters of reference refer to like parts in the two figures.

25 A represents the main or body portion of the bottle, provided at the top with a short outlet-neck *a*. To this body portion is attached a neck portion B, the two parts being fastened together by a joint of such nature that it can- 30 not be readily broken or when once broken the parts cannot be easily put together again without special appliances. This joint, as I propose to make it, comprises annular flanges at the top and bottom of the parts A and B,

35 respectively, where they come together, with a rubber or other gasket C placed between. In joining the parts together after the body portion has been filled with the liquid the neck portion B is set in place and pressed down so

40 as to compress the gasket C between the flanges on the two parts. A metal flanged ring D is then slipped down around the flanges and pressed in at top and bottom to firmly clasp the flanges together. It will be evident that 45 this form of joint cannot be broken and put together again without special appliances, for in removing the ring D said ring will be either broken or so mutilated as to prohibit its being used again, thereby necessitating the use of a

50 new ring, which, moreover, requires special

tools for fitting it into place. The joint between the parts as so made is firm and tight and there can be no leakage of air or liquid therethrough. While I have described this as my preferred manner of joining the parts, 55 I do not desire to be limited in this respect, as the parts may be otherwise sealed together without departing from the spirit of my invention.

The non-refilling device consists, primarily, 60 of the hood or cap-piece G, which covers and surrounds the neck *a* of the body portion A, the base of the hood being placed below the top of said neck and spaced away from it so as to provide a passage for liquid around the 65 base into the neck portion B. As illustrated, this hood is substantially conical in shape and is secured to the neck *a* by a screw-threaded ring H, to which it is attached by means of a number of webs I. The hood, however, may 70 be otherwise shaped and may be secured in place with relation to the neck *a* in other ways. The outlet through neck *a* is provided at the outside with a valve E, said valve being provided with wire guides F to keep it 75 in place when opening and closing. Resting upon the valve within the hood is a ball J of some little weight. The valve E and hood G may be of glass or any other suitable material, and I preferably seat the valve upon the 80 rim of neck *a* upon a knife-edge, as indicated, in order to prevent the valve from sticking thereto.

In use when pouring a liquid from the bottle upon turning the bottle on its side the 85 weight of the liquid will throw the valve E and ball J outward into the hood G, allowing the liquid to run out from the neck *a* into the hood and around the lower edge thereof into the neck portion B, air passing in around that 90 part of the cap which is uppermost to permit the liquid to run freely from the bottle. When the bottle has been emptied, it will be evident that it cannot be filled again without removing the neck portion B, hood G, and 95 valve E. For if it be attempted to fill the bottle with these parts in place the ball J will hold the valve closed, except when the bottle is held upside down or so nearly in that position as to prevent any liquid from being forced into 100

the body portion A. If it be attempted to refill the bottle when lying on its side, the ball J, resting as it will against the inclined sides of the hood G, will press the valve E 5 against its seat and hold it there, the weight of the liquid which is attempted to be run in through the neck B also assisting in pressing the valve to its seat. Even without the valve and ball the hood G, by reason of its 10 position with relation to the neck a, will prevent the bottle from being refilled in the ordinary ways of pouring in through the neck, since the base of the hood lies below the top of neck a and forms a trap which prevents 15 the escape of air from the body portion. Some liquid may be forced into the body portion by immersing the bottle on its side in a bath of the liquid when the hood only is used; but the bottle cannot be more than half-filled 20 in this way, and it will not be worth while. By this arrangement it will be seen that I have produced an effective device for preventing the refilling of the bottle, such device consisting of a minimum number of parts very simple 25 in their construction and manner of operation. A bottle so constructed will effectually prevent the adulteration of the contents of the body portion A or the refilling thereof when once emptied, since for practical purposes no 30 liquid can be run into the body portion without removing the neck B and hood G. Moreover, it will be observed that there is a full and clear passage for the liquid through the neck B and ample passage-ways from neck a 35 around the hood into neck B, so that there will be the same freedom of flow as in an ordinary bottle.

Having thus described my improvements, what I claim as my invention, and desire to secure by Letters Patent, is—

1. In a non-refillable bottle, a body portion closed at the top by a head provided with an

outlet at its center, a neck portion having a flaring base secured to the body portion at the outside diameter thereof by a sealed joint, and means for preventing the entrance of liquid from the neck portion into the body portion through said outlet, said means being inclosed within the flare of the neck portion and separated therefrom to form a clear passage-way 45 50

2. In a non-refillable bottle, a body portion closed at the top by a head at the center of which is an outlet surrounded by a short neck, a neck portion having a flaring base covering 55 said head and secured to the body portion by a sealed joint, a valve to close the outlet through said head, a substantially conical hood or cap above the outlet-neck, there being a passage for liquid from said outlet to the neck 60 portion around the base of the cone, and a ball within the cone to press the valve to its seat.

3. In a non-refillable bottle, a body portion and a neck portion, the body portion having an outlet into the neck portion, and a hood or 65 cap within the neck portion covering said outlet, the base of said hood being positioned below the top of said outlet and there being a passage for liquid from said outlet to the neck portion around said base.

4. In a non-refillable bottle, a diaphragm below the flare of the neck provided with a central orifice, and a hood or cap positioned above said orifice, the base of said hood being located below the top of said orifice and forming a passage-way for liquid from said orifice to the neck around said base.

In testimony whereof I have affixed my signature in presence of two witnesses.

ETNA H. DAVIS.
